UNITED STATES PATENT OFFICE.

THOMAS W. COUGHLIN, OF BINGHAMTON, NEW YORK.

HEAD-REST FOR CASKETS.

SPECIFICATION forming part of Letters Patent No. 628,649, dated July 11, 1899.

Application filed October 1, 1898. Serial No. 692,455. (No model.)

To all whom it may concern:

Be it known that I, THOMAS W. COUGHLIN, a citizen of the United States, residing at Binghamton, in the county of Broome and State 5 of New York, have invented certain new and useful Improvements in Head-Rests for Caskets, of which the following is a specification.

My invention relates to improvements in head-rests for caskets; and the object of my 10 improvements is to provide a head-rest by which the head and shoulders of a body can be raised and lowered readily. I attain this object by means of the mechanism illustrated in the accompanying drawings, in which—

15 Figure 1 is a perspective view of my head-rest in an elevated position, and Fig. 2 is a similar view of it lowered to its lowest plane.

In Fig. 1, A represents the main body of my rest; B, the head-rest proper; C, the lower 20 supporting-legs; D, the middle supporting-legs; E, the higher supporting-leg; F, the middle auxiliary legs; G, the higher auxiliary leg; H, the cross-rod; I, the ears; J, the twisted center; K, the upper extension; L, the head-ring, and X the toes of the legs. In Fig. 2 the 25 same letters indicate the same parts.

My support is made of stiff wire, which is 30 twisted or pressed into the form desired and the different parts connected. The main body A is composed of a wire bent in the form of an elongated X, the top of which is continuous, forming the straight horizontal cross-bar H between the two sides, which extend upward in the two open loops I. The wire then 35 crosses itself about the center J, where it is intertwined, and ends in the two legs C, bent under and backward and provided with the sharp toes X. Around the outward ends of the cross-bar H is twisted the two ends of the 40 extension K, the ends extending downward to form the legs D and the upper part of which drops to form the auxiliary legs G and then, meeting in the center, extend to form the ring L, below which the two wires are inter-

twisted and run together in the neck B to the 45 center of the rod H, around which they are immovably clamped. The leg E is simply a straight rod secured movably at one end to the ring L and having the sharp toes X. The legs D are made of a continuous wire bent at 50 right angles, the top of which is bent around the rod H, to which it is movably clamped. When in the position indicated in Fig. 1, a body placed upon it is raised up in a casket and when it is desired to lower it the legs D 55 and E are pushed forward and the support is lowered till it rests upon the auxiliary legs F and G.

What I claim as my invention, and desire Letters Patent for, is—

1. In a head-rest for caskets, the frame A provided with the legs C, the ears I, and the rod H in combination with the extension-frame K provided with the auxiliary legs F and G, and the ring L; and the legs D and E; 60 as described and specified.

2. In a head-rest for caskets a wire frame made to support the body at a desired angle by means of movable vertical legs of different lengths located in different parts of the frame 70 and provided with sharpened points to prevent their slipping on the bottom of the casket; in combination with a rigid wire frame having sharpened points at its lower extremities to engage the bottom of the casket and 75 relatively short auxiliary rigid legs at its upper end to support it when let down, at a slight angle above the casket-bottom: said frame at its upper end being shaped to receive and hold the head, the lower part spreading 80 out laterally to support the shoulders the lower end narrowing; the head-frame and the body-frame being rigidly connected as described and specified.

THOMAS W. COUGHLIN.
